UNITED STATES PATENT OFFICE.

ALFRED C. GILBERT, OF NEW HAVEN, CONNECTICUT, ASSIGNOR, BY MESNE ASSIGNMENTS, TO THE A. C. GILBERT COMPANY, OF NEW HAVEN, CONNECTICUT, A CORPORATION OF MARYLAND.

ELECTRIC HEATER.

Application filed February 5, 1926. Serial No. 86,243.

This invention relates to improvements in electric heaters of the radiant or reflector type, and it has for its primary object to provide a heater of this character which will be inexpensive to manufacture and efficient and safe in operation.

Another object of the invention is to provide a heater of this type, having a minimum number of parts and wherein all heated or breakable parts are amply protected against interference.

Still another object of this invention is to provide improved means for holding the parts constituting the heater together, whereby a rigid structure is formed which is free from the possibility of the same becoming loosened and dislocated relatively to each other.

To these and other ends, the invention consists in the novel features and combinations of the same to be hereinafter described and claimed.

In the accompanying drawings:

Fig. 1 is a vertical section through the parts constituting the heater, certain parts not being shown in section for the sake of clearness;

Fig. 2 is an enlarged front face view of the parts of the heater, which support the heating element and the holder therefor, the heating element being omitted;

Fig. 3 is an enlarged vertical section on line 3—3 of Fig. 2, the heating element and the holder therefor not being in section for the sake of clearness, and

Fig. 4 is a section on line 4—4 of Fig. 1.

The heater illustrated in the drawings comprises a concave reflector 10, which is pivotally secured to a pedestal or standard 11, a heating element 12 connected to a power source, (not shown) by means of the usual electrical connections within the holder or socket 13, through the wires 14, and a guard 15 which surrounds the heating element and lies wholly within the reflector 10. The arrangement of the parts and the structure of the heater, as generally outlined above, is the subject matter of a co-pending application No. 594,843, filed October 16, 1922, in the name of Alfred C. Gilbert. The present application contemplates improvements over the heater described in the aforesaid application.

The reflector 10 is constructed of one piece

of sheet metal pressed into the form of a segment of a hollow sphere, and at the peripheral edge thereof is provided with a back-turned flange 16. The reflector has an opening 17 disposed substantially in the center thereof for a purpose to be herein-after described. Below the opening 17 the reflector is pivotally secured to the pedestal 11 by means of a pair of L shaped members 18, which are spaced apart so that the depending portions 19 thereof will straddle the end of the upright portion 20 of the pedestal to which they are secured by means of a bolt 21 and thumb nut 22, upon flattened portions 23, formed in the sides of the upright portion 20 at the upper end thereof. The L shaped members 18 are secured to the reflector by means of bolts 24.

The pedestal 11 is formed from one piece of sheet metal, the upright portion 20 being hollow and generally cone-shaped, being struck upwardly from the base portion 25. The peripheral edge of the base is turned outwardly as at 26, forming a shoulder 27 upon which a disk 28 for closing the open mouth at the base is clamped by turning the edge inwardly about the disk as at 29.

The guard 15 is formed of radially extending wires 30, which converge and are attached at one end to a washer 31. The other ends of these wires also converge and are secured to a member 32, the use and form of which will be hereinafter described. Between the converging ends of the wires 30 is an annular ring of wire 33, over which the wires 30 extend and which holds the wires 30 outwardly about and away from the heating element 12.

The socket member 13 has an outer casing of insulating material 34, in which the electrical connecting means for the heating element are located, in this instance, being of the well known screw thread lamp socket type. The socket casing 34 is provided with an annular rib 35 of larger diameter than the body of the socket casing, whereby oppositely directed shoulders 36 and 37 are formed at each side of the rib 35. A portion 38 of the body of the socket casing extends beyond one side of the rib 35, and a portion 39 extends beyond the other side of the rib 35. In the instance illustrated, the rib 35 is a frustum of cone shape, the taper of which is toward the casing portion 38.

The member 32 is formed from a piece of sheet metal, and at its center portion is adapted to fit over the socket casing rib portion 35, as at 40. An inturned edge portion 41 is provided about a central opening 42. The inturned edge portion 41 rests upon the shoulder 36 formed by the rib 35, and the casing portion 38 extends through the opening 42. The member 32 is extended laterally from the rib fitting portion 40 as at 43 and is then turned rearwardly to form the flange 44. In this instance, the member 32 is substantially circular in form and the portion 40 is a frustum of cone shape. The laterally extending portion 43 encircles the base of the portion 40, and the flange 44 is in the form of an annulus and provides a rearwardly directed edge 45. The converging ends of the wires 30 above mentioned as being secured to the member 32, are secured to the portion 43 thereof by passing through openings therein and then being bent over, as at 47.

The socket member 13 is clamped to the reflector 10, by means of the member 32 and the use of bolts 46 which pass through openings in the laterally extending portion 43 of the member 32, between the inturned edge 41 and the reflector material around the opening 17 in the reflector. An especially tight clamping action is provided, due to the edge 45 being in contact with the reflector surface, the bolts 46 being free to spring the material of the portion 43 toward the reflector, thereby causing a continuous clamping strain to be placed upon the shoulder 36 by the portion 41 of the member 32.

The portion 39 of the socket member 13 extends through the opening 17 of the reflector 10, and being thus disposed the electrical connections thereon would be exposed. To avoid this, a closure member 52 is provided for the opening 17. The closure member 52 is generally cup-shaped and has a laterally extending flanged edge 48 about the open mouth thereof. In the instance illustrated, this flange is interposed between the shoulder 37 of the socket casing and the reflector material about the opening 17 therein, whereby it is clamped between the same when the socket is clamped to the reflector by the bolts 46. The cup shaped portion 49 of the closure member 52 extends rearwardly through the opening 17 and is provided with an opening 50 substantially in the center thereof into which an insulating bushing 51 is placed for the protection of the wires 14 which pass therethrough.

I do not claim herein the broad combination of elements in a heater of the type described including a concave reflector, a heating element, a heating element support, and a guard for said heating element which surrounds the same and lies wholly within the reflector, or the form of guard, or, broadly,

the means to secure the guard and the heating element support to the reflector, or other features claimed in my co-pending application, Serial No. 594,843, filed October 16, 1922.

While I have illustrated and described a preferred form of my invention, it is to be understood that the same is not limited to the exact details shown, but is capable of many modifications and variations which will lie within the spirit of the invention and the scope of the appended claims.

What I claim is:

1. In an electric heater of the type described, a reflector having an opening 80 through a portion thereof, a heating element support having a portion presenting a shoulder, said shoulder resting upon the reflector about the opening therein, another shoulder upon said support, a member engaging the 85 second mentioned shoulder and having a portion overlying the reflector, and means to secure the portion of said member overlying the reflector to clamp the support to said reflector.

2. In an electric heater of the type described, a reflector having an opening through a portion thereof, a heating element support having a laterally projecting portion presenting a pair of oppositely directed shoulders, one of said shoulders being adapted to engage the reflector adjacent the edge of the opening therein, a member engaging the other shoulder and having a portion adapted to overlie the reflector, and means to secure the overlying portion thereof to the reflector, whereby the support is retained in position upon said reflector.

3. In an electric heater of the type described, a reflector having an opening 105 through a portion thereof, a heating element support having an annular rib whereby oppositely directed shoulders are formed thereon, one of said shoulders being adapted to rest upon the reflector material about the 110 opening therein, an annular ring about said support having an inwardly directed flange in engagement with the other shoulder, said ring having an outwardly directed flange overlying said reflector, and means to secure said outwardly directed flange to said reflector.

4. In an electric heater of the type described, a reflector, a heating element, a support for said heating element, and a wire 120 guard about said heating element, and including a member secured to said reflector, said member being adapted to support said heating element support and said wire guard.

5. In an electric heater of the type described, a reflector, a heating element having a threaded end, a threaded socket member for said heating element, said socket member having a projection upon the body 130

thereof and a member having a portion in engagement with said projection and another portion overlying said reflector, and means to secure the overlying portion to said reflector whereby said socket is secured to said reflector.

6. In an electric heater of the type described, a reflector, a heating element, a socket for holding said heating element, said socket including in its structure an outer casing having an annular rib about the body thereof, and a guard for said heating element having a base-plate, said base-plate having a portion in engagement with said annular rib, and another portion overlying said reflector, and means to secure the overlying portion of said plate to said reflector whereby said guard and said socket are secured together and to said reflector.

7. In an electric heater of the type described, a reflector having an opening therethrough in substantially the center thereof, a heating element, a socket member for said heating element having an outer casing, said casing having a body portion adapted to extend through the opening of said reflector, and a rib encircling said body portion intermediate the ends thereof, said ribs providing a pair of oppositely directed shoulders, a member encircling said casing and having a laterally extending part in engagement with one of said shoulders, and a laterally extending part overlying the surface of said reflector, means to secure said member to said reflector and radially extending wires secured to said last mentioned laterally extending part of said member and adapted to surround said heating element as a guard therefor.

8. In an electric heater of the type described, a reflector having an opening therethrough in substantially the center thereof, a heating element, a socket member for said heating element having an outer casing, said casing having a body portion adapted to extend through the opening of said reflector, and a rib encircling said body portion intermediate the ends thereof, said rib providing a pair of oppositely directed shoulders, a member encircling said casing and having a laterally extending part in engagement with one of said shoulders, and a laterally extending part overlying the surface of said reflector, a cover for the opening in said reflector having a laterally extending part overlying the surface of said reflector and adapted to receive the casing body extending therethrough, and means to simultaneously secure said socket, said member and said cover to said reflector.

9. In an electric heater of the type described, a concave reflector having an opening in the center thereof, a heating element, a heating element support including a rearwardly directed shoulder, a guard for said

heating element including a member adapted to engage said support forward of said shoulder, to clamp said shoulder against the reflector portion surrounding the center opening therein, and means to secure said member to said reflector.

10. In an electric heater of the type described, a concave reflector, a heating element, a heating element support, a guard for said heating element including a part adapted to engage said support to hold the same relatively to said guard, and means to secure said guard part to said reflector to retain said support relatively thereto.

11. In an electric heater of the type described, a concave reflector having an opening in the center thereof, a heating element, a heating element support having a rearwardly directed end portion extending therefrom through the opening in said reflector, a cap for said support end portion extending through the same opening and having a part engaging the reflector about the same opening, a part of said support engaging said cap part, a guard for said heating element including a part adapted to engage said support, and means to secure said guard part to said reflector to retain said support and cap thereto.

12. In an electric heater of the type described, a concave reflector having an opening in the center thereof, a heating element support having a rearwardly directed end portion extending therefrom through the opening in said reflector, a cap for said support end portion extending through the same opening and having a part engaging the reflector about the same opening, a part of said support engaging said cap part, and means engaging said support to secure it and said cap to said reflector.

13. In an electric heater of the type described, a reflector, a heating element, a support for said heating element, and a guard about said heating element, said guard including a member secured to said reflector, said member engaging said support to secure it and said guard to said reflector.

14. In an electric heater of the type described, a concave reflector having an opening in the center thereof, a heating element support having a rearwardly directed end portion extending therefrom and through the opening in said reflector, a cap for said support end portion having a part engaging the reflector about the same opening, and means to secure said support and said cap to said reflector, including a part in engagement with said support.

15. In an electric heater of the type described, a concave reflector having an opening in the center thereof, a heating element, a heating element support including a rearwardly directed shoulder, a member adapted to engage said support forward of said

shoulder to clamp said shoulder against the reflector portion adjacent the opening therein, and means to secure said member to said reflector.

5. 16. In an electric heater of the type described, a concave reflector having an opening in the center thereof, a heating element support having a rearwardly directed end portion extending therefrom and through 10 the opening in said reflector, a cap for said support end portion having a part engaging the reflector about the same opening, and a guard for said heating element including a part adapted to engage said support, and 15 means to secure said guard part to said reflector to retain said support and cap thereto.

17. In an electric heater of the type described, a concave reflector having an opening in the center thereof, a heating element, 20 a heating element support including a rearwardly directed shoulder, and a rearwardly directed end portion extending through the opening in said reflector, a cap for said support end portion having a part engaging said reflector about the same opening, a member adapted to engage said support forward of said shoulder, and means to secure 25 said member, said support and said cap to said reflector.

18. In an electric heater of the type described, a concave reflector having an opening adjacent the center thereof, a heating element extending outwardly from said reflector, a socket engaging the inner end of 30 said heating element to support the same, means to secure said socket to said reflector including an annular plate in engagement

with said socket, means to secure said plate to said reflector, and wire-like members secured to said plate and extending outwardly and converging beyond the outer end of 40 said heating element to form a guard therefor.

19. In an electric heater of the type described, a concave reflector having an opening adjacent the center thereof, a heating element extending outwardly from said reflector, a socket engaging the inner end of 45 said heating element to support the same, means engaging said socket to secure it to 50 said reflector, and members secured to and extending outwardly from said socket securing means and converging beyond the outer end of said heating element to form a 55 guard therefor.

20. In an electric heater of the type described, a concave reflector having an opening adjacent the center thereof, a heating element extending outwardly from said reflector, a socket engaging the inner end of 60 said heating element to support the same, means to secure said socket to said reflector including an annular plate in engagement with said 65 socket, means to secure said plate to said reflector, a supporting ring spaced from and surrounding said heating element intermediate the ends thereof, and wire-like members secured to said plate and extending outwardly and over said supporting ring and 70 converging beyond the outer end of said heating element to form a guard therefor.

In witness whereof, I have hereunto set my hand this 2d day of February, 1926.

ALFRED C. GILBERT
